UNITED STATES PATENT OFFICE.

GEORGE R. CORNWALL, OF RYE, NEW YORK, ASSIGNOR TO AMERICAN PLANOGRAPH COMPANY, A CORPORATION OF WEST VIRGINIA.

PROCESS OF PRODUCING LETTER-PRESS PRINTING PLATES OR FORMS.

1,106,369.

Specification of Letters Patent. Patented Aug. 11, 1914.

Application filed July 21, 1906, Serial No. 327,131. Renewed November 8, 1912. Serial No. 730,270.

To all whom it may concern:

Be it known that I, GEORGE R. CORNWALL, a citizen of the United States, residing at Rye, in the county of Westchester and State 5 of New York, have invented new and useful Improvements in Processes of Producing Letter-Press Printing Plates or Forms, of which the following is a specification.

The invention relates to the production of 10 printing plates or forms, and in many of its features more especially to a process for producing letter-press printing plates or forms.

Objects of the invention are to provide a 15 novel process for producing a plate or form of excellent quality in an expeditious, economical and simple manner, while at the same time allowing all desirable latitude for the making of changes either by way of 20 addition, subtraction, substitution, transposition, or otherwise, as may be necessary or desirable in order to bring the composed matter into the desired final state prior to making the printing plate. These and other 25 objects of invention will in part be obvious from, and will in part more fully appear from, the description and claims.

The invention consists in the novel steps, 30 processes, and improvements herein illustrated and described.

The accompanying drawings, referred to herein and forming a part of this specification, illustrate one manner of carrying out certain steps included within the invention.

35 Of the drawings: Figure 1 represents an impression-receiving surface bearing lines of characters representing a composition; Fig. 2 represents the impression of the lines of characters from the impression-receiving 40 surface to the surface of line bars carried in a form; Fig. 3 represents inking the line bars; Fig. 4 represents the taking of a proof impression; Fig. 5 represents the proof sheet; Fig. 6 represents the inking up of the 45 corrected form of line bars; Fig. 7 represents taking an impression from the corrected form of bars upon an impression-receiving surface; Fig. 8 represents the transfer of 50 the composed matter from the impression-receiving surface to the surface of a sensitized plate; and Fig. 9 represents the completed plate.

The process included in the present invention 55 contemplates the production of a letter-press printing plate, which may be plano-

graphic or otherwise, by the use of line bars having sensitized surfaces, but which are not necessarily of a light-transmitting material; the process contemplates further the giving of every facility for the correction 60 of proof and the making of any changes necessary or desirable in order to bring the composed matter into the desired final state or condition, whether such changes are by way of additions to, or subtractions from, 65 the said line bars, substitutions of one bar for another, transpositions of the line bars, or otherwise; the invention, in some of its features, further contemplates utilizing matter which has been composed in various 70 ways, such as a line at a time, or letter by letter, or placed primarily upon the line bars.

The invention includes also other features 75 than those specifically set forth above.

In the manner of carrying out certain steps of the process, as illustrated in the accompanying drawings, 1 represents the impression-receiving surface upon which are shown in series lines of characters, indicated 80 by the reference numeral 2, constituting a composition. The said lines of characters may, if desired, be justified, and ordinarily will be so justified. The impression-receiving surface 1, according to certain features 85 of the invention, will be of a material that transmits light with more or less readiness, and for this purpose it will generally be found convenient to use a paper which is highly translucent. It will be understood, 90 however, that various other materials will be found suitable for the impression-receiving surface so far as regards many features of the invention. With a paper of the kind described the characters of the composition 95 are placed thereon in a substantially opaque medium. It will be understood, therefore, that when a sensitized surface is exposed to the action of light through the impression-receiving medium, the characters and the surrounding surface will have an opposite 100 effect upon the sensitive surface, the action of the light thus serving to define the characters and the surrounding surface upon the said sensitive surface.

In Fig. 2 of the drawings is shown a series of line bars 3, which for convenience, have been assembled into a form, and upon which the lines of characters from the impression-receiving surface are being im- 110

pressed by the action of light. In the present instance the light used in so impressing the characters is transmitted light, although this may be done by reflected light, utilizing the camera if desired, so far as regards some features of the invention. In the said figure the bars are shown conveniently held together by a chase 4. The bars are also spaced apart by leads 5. The impression-receiving surface 1 is shown in contact with the surface of the bars and may be conveniently held in contact therewith with the assistance of a transparent plate 6. Suitable fastening devices, such as clamps 7, may be utilized, if desired, to hold the said parts in fixed and convenient position with reference to each other. A suitable source of light is indicated by the reference numeral 8.

Suitable means may be used in connection with the carrying out of this invention for properly positioning the lines of characters upon the surface of the line bars. A form of means for effecting this is shown herewith as comprising means upon the impression-receiving sheet in definite relation to the lines of characters and means upon the line bars of the chase in definite relation to the line bars. The particular form of such means shown in the illustrated embodiment comprises registering holes 9 on the sheet and corresponding pins 10 upon the bars. Furthermore, the chase is shown as provided with suitable devices for positioning the bars in definite relation with respect to each other and also in definite relation with the registering means carried by the chase. The form of said means herein shown comprises beveled ends 11 upon the bars fitting into corresponding beveled faces upon the chase. Various kinds of line bars may be found convenient or desirable for use, such as metal line bars, or those of various other materials. The surface of the bars may be sensitized in various ways. If desired, the said bars may be sensitized by means of a coating of sensitive asphalt, which may be merely poured over their surface in a suitable manner. It will frequently be found convenient to use as a sensitizer for the surface of the bars a chromated colloid, such as chromated albumen or gelatin, sensitizers of this kind being well known in the photo-mechanical art. One way of preparing such a sensitizer is by dissolving in suitable proportion ammonium bichromate, and by dissolving commercial albumen in suitable proportions in another solution. The said solutions may then be thoroughly mixed, a little ammonium being added thereto, and after filtering, the solution may be poured upon the surface of the bars and allowed to dry thereon in a thin layer or coating. After being exposed to the light the line bars may be suitably developed in a manner dependent upon the kind of sensitizer that has been

used. Where the sensitizer is asphaltum the developer used may be turpentine; where the sensitizer used is the chromated albumen the developer may be simply water. The particular process of the development in each case is known to the art and, simply as such, is not a part of the present invention. The result in either case is to give the characters and the surrounding surface different properties with respect to taking or rejecting ink. In the present instance, where opaque characters are placed upon a translucent impression-receiving medium and following the steps of the process, as herein generally set forth, the character will be ink rejecting in its properties and the surrounding surface ink receiving. The line bars may then be inked in any suitable manner, the step of inking being shown in a general way in Fig. 3 of the drawings, as being performed by a hand roller. This figure shows the characters as being ink rejecting and the remainder of the surface of the bars as ink taking. The leads 5, when used, may also be of such nature as to take ink readily, if desired, and are so shown in Fig. 3 of the drawings.

As in most letter-press matter the making of such changes of various kinds as are necessary to bring the matter into the desired final state or form are of great importance, the invention in certain of its aspects contemplates providing means for effecting this. The said features of the invention contemplate the taking of a proof impression to assist in making the changes which are necessary or desirable, as aforesaid, in bringing the matter into the desired final condition. Accordingly, in Fig. 4 of the drawings, is shown a proof impression being taken from the form of bars 3 upon a suitable sheet 12. The impression in this particular instance, is shown as being made by a hand roller 13, although any suitable means, such as a proof press, may be employed, if desired. A proof from the line bars of the kind described, will give a white letter upon a black ground. If a proof having black letters upon a white ground is desired, photographic proofs may be taken from a sheet which has been printed or impressed from the line bars, or such impressed sheet may be used as a negative to secure a sensitized plate from which any desired number of impressions may be taken having the black letter upon the white ground. For most uses of proof reading, however, it will be found that there is no well-founded objection to the proof as taken from the line bars with the white letter upon the black ground. If the composition is placed upon the original impression-receiving surface by certain composing agencies known to the art it will be found that wrong font letters and broken letters and many other sources of error com-

paratively difficult to detect are entirely eliminated, as it is practically impossible for them to occur with certain classes of composing devices.

The general principles of changing the line bars so as to bring the composition into the desired final condition are generally the same and, for the purpose of illustration, the change to be made is shown in the drawings as involving the correction of a typographical error, occurring in the first line and indicated in Fig. 1 of the drawings and also in Fig. 5 by the reference numeral 14. A proof reader's mark 15, indicating the correction, is shown in the margin, in Fig. 5 of the drawings, upon the proof sheet 12.

In Fig. 6 of the drawings is shown the form of line bars with a corrected line bar substituted for the incorrect one, previously indicated, and so far as the present instance is concerned the matter being then in the desired final state or condition. The correct matter upon the new line bar is indicated by the reference numeral 16. After the matter is in the desired final form or condition the line bars may be again inked and this is shown in a general way in Fig. 6 of the drawings, the inking being done by means of a hand roller 17. An impression is then taken from the form of line bars upon an impression-receiving surface, or medium, of a suitable kind and, so far as certain features of the invention are concerned, the said impression-receiving surface may also be of a paper which is translucent or light transmitting or transparent.

In Fig. 7 of the drawings such an impression-receiving material or surface is indicated by the reference numeral 18, the pressure between the said material and the surface of the bars being supplied in any suitable manner, as, for instance, by the hand roller 19. A printing plate of suitable material is selected and where the final form or plate is to be planographic such plate may be of aluminum or zinc. As the process, however, may be extended to securing a relief plate by etching, or otherwise, plates of other material, such as copper, may be used, if desired. It may be considered that the plate is one for planographic printing, in which case it will probably be of zinc or aluminum. After being suitably prepared, as by graining, or otherwise, the surface of the plate may be sensitized. The sensitizing may be done in different ways, as for instance, by one of the processes herein described in connection with the surface of the line bars. The composed matter may be transferred from the impression-receiving surface to the surface of the plate by the action of light. This may be done by the action of light transmitted through the impression-receiving material or surface 18, if desired, or by re-

flected light with the camera or otherwise. In the manner of carrying out the steps of the invention, illustrated in the accompanying drawings, the action is shown as occurring through the agency of transmitted light.

In Fig. 8 of the drawings a suitable plate 20 is shown having the impression-receiving material 18 in contact therewith, a suitable light-transmitting plate 21 being placed over the plate 20 and surface 18 to hold them in position, a support 22 being also provided for the plate 20. There is shown in the drawings clamping devices 23 for holding them together, and a source of light is indicated generally by the reference numeral 24. After being impressed with the characters of the composed matter the plate may be suitably developed in various ways. With the asphaltum, as hereinbefore noted, turpentine may be used as a developed; while with the albumen water may be used. It will be understood that with the particular manner of carrying out the invention described and illustrated the impression-receiving surface 18 will show a white letter upon a black background and the plate 20 will consequently show a black letter upon a white background, that is a background which will print "white" or clear. The surface of the plate may then be prepared for printing by rolling up and gumming if the plate is to be used planographically. If a relief plate is desired, however, an acid resist may be applied to the surface of the plate and the plate may be etched into relief in a manner well known to the art.

While the invention has been described in connection with line bar units, it is applicable, and is also believed to be novel, with respect to composing units broadly, and in certain of its aspects the invention will be understood as not being limited to line bar units.

From all the foregoing it will be understood that a process has been disclosed in a manner sufficiently clear to enable those skilled in the art to practise same, said process realizing the objects of invention and the advantages herein set forth, together with other objects and advantages. It will be further understood that the process is not limited to the particular manner of carrying out the steps thereof illustrated and described herein, as changes may be made in many ways without altering the scope of the invention.

What I do claim as my invention and desire to secure by Letters Patent, is:

1. The process of producing a letter-press printing plate or form which comprises placing upon an impression-receiving surface lines of characters representing a composition, assembling into a form a series of line bars or units having light-sensitive surfaces,

imposing upon the surface of the said line units the lines of characters from the impression-receiving surface by the action of light, so that a line of characters will be impressed upon each of the said line units, developing the surfaces of the said line units, making such changes in the said line units as may be necessary or desirable to bring the composed matter to the desired final state, inking the surfaces of the line units, taking an impression therefrom upon an impression-receiving surface, sensitizing the surface of a printing plate, transferring the composed matter from the said impression-receiving surface to the surface of the said plate by the action of light, and preparing the said plate for printing.

2. The process of producing a letter-press printing plate or form which comprises placing upon an impression-receiving surface lines of characters representing a composition, assembling into a form a series of line bars or units having light-sensitive surfaces, imposing upon the surfaces of the said line units the lines of characters from the impression-receiving surface by the action of light, so that a line of characters will be impressed upon each of the said line units, developing the surfaces of the said line units, inking the surfaces of the line units, taking an impression from the said line bars for use in determining what changes are necessary or desirable in order to bring the composed matter into the desired final state, making such changes by way of additions, subtractions, substitutions, transpositions, or otherwise, in the said line units as may be necessary or desirable to bring the composed matter to the desired final state, inking the surfaces of the line units, taking an impression therefrom upon an impression-receiving surface, sensitizing the surface of a printing plate, transferring the composed matter from the said impression-receiving surface to the surface of the said plate by the action of light, and preparing the said plate for printing.

3. The process of producing a letter-press printing plate or form which comprises placing upon a light-transmitting impression-receiving surface lines of characters representing a composition so that the characters and the surrounding surface will possess opposite properties with respect to the transmission of light, sensitizing the surface of certain line units, assembling the said line units into a form, exposing the sensitized surface of the said line units to the action of light through the sheet of impression-receiving material so that a line of characters will be impressed upon each of the said line units, developing the surface of the said line units, making such changes by way of additions, subtractions, substitutions, transpositions, or otherwise, as may be necessary

or desirable in order to bring the composed matter into the desired final state, taking an impression from the said line units upon a light-transmitting, impression-receiving surface in such manner that the characters and the surrounding surface of the impression-receiving material will possess opposite properties with respect to the transmission of light, sensitizing the surface of a printing plate, subjecting the sensitized surface of the said plate to the action of light through the impressed sheet of impression-receiving material, and preparing the surface of the said plate for printing.

4. The process of producing a letter-press printing plate or form which comprises placing upon a light-transmitting impression-receiving surface lines of characters representing a composition so that the characters and the surrounding surface will possess opposite properties with respect to the transmission of light, sensitizing the surface of certain line units, assembling the said line units into a form, exposing the sensitized surface of the said line units to the action of light through the sheet of impression-receiving material so that a line of characters will be impressed upon each of the said line units, developing the surface of the said line units, inking the surface of the said line units, taking a proof impression therefrom for use in determining what changes are necessary or desirable in order to bring the composed matter into the desired final state, making such changes by way of additions, subtractions, substitutions, transpositions, or otherwise, as may be necessary or desirable in order to bring the composed matter into the desired final state, inking the said line units, taking an impression from the said line units upon a light-transmitting, impression-receiving surface in such manner that the character and the surrounding surface of the impression-receiving material will possess opposite properties with respect to the transmission of light, sensitizing the surface of a printing plate, subjecting the sensitized surface of the said plate to the action of light through the impressed sheet of impression-receiving material, and preparing the surface of the said plate for printing.

5. The process of producing a letter-press printing plate or form which comprises impressing upon a light-transmitting sheet lines of characters in an opaque medium, assembling into a form a series of line units having light-sensitive surfaces, exposing the sensitive surfaces of the line units to the action of light through the said impressed sheet, so that a line of characters will be carried upon each of the said line units, developing the surfaces of the said light-sensitive units so that the surface of the said line units will carry the line of char-

acters thereon, making such changes in the said line units by way of additions, subtractions, substitutions, transpositions, or otherwise, as may be necessary or desirable 5 to bring the composed matter into the desired final state, sensitizing the surface of a printing plate, tranferring the lines of characters from the said line units to the surface of the said plate, developing the surface of 10 the said plate, and preparing the plate for printing.

6. The process of producing a letter-press printing plate which comprises placing upon an impression-receiving surface lines of 15 characters representing a composition, assembling into a form a series of line bars or units having light-sensitive surfaces, imposing upon the surfaces of the said line units the lines of characters from the im- 20 pression-receiving surface by the action of light, so that a line of characters will be impressed upon each of the said line units, developing the surface of the said line units, making such changes in the said line units 25 as may be necessary or desirable to bring the composed matter into the desired final state or condition, inking the surface of the line units, and transferring the composed matter from the said line units to a printing 30 plate, and preparing the said plate for printing.

7. The process of producing a letter-press printing plate which comprises placing upon an impression-receiving surface lines of 35 characters representing a composition, assembling into a form a series of line bars or units having light-sensitive surfaces, imposing upon the surfaces of the said line units the lines of characters from the impression- 40 receiving surface by the action of light, so that a line of characters will be impressed upon each of the said line units, developing the surface of the said line units, making such changes in the said line units as may 45 be necessary or desirable to bring the composed matter into the desired final state or condition, inking the surface of the line units, sensitizing the surface of a printing plate, transferring the composed matter

from the said line units to the surface of the 50 said plate, and preparing the said plate for printing.

8. The process of producing a letter-press printing plate or form which comprises placing lines of characters representing a 55 composition upon the line bars assembled into a form, making any changes necessary or desirable to bring the composed matter to the desired final state or condition, inking the surface of the said line units, taking 60 an impression therefrom upon an impression-receiving surface, sensitizing the surface of a printing plate, transferring the composed matter from the said impression-receiving surface to the surface of the said 65 plate by the action of light, and preparing the said plate for printing.

9. The process of producing a letter-press printing plate or form which comprises placing upon a light-transmitting impres- 70 sion-receiving surface lines of character in an opaque medium, said lines of characters representing a composition, assembling into a form a series of line bars or units having light-sensitive surfaces, imposing upon the 75 surfaces of the said line units the lines of characters from the impression-receiving surface by the action of light, so that a line of characters will be impressed upon each of the said line units, developing the sur- 80 faces of the said line units so that the characters will be ink rejecting and the surrounding surface ink taking, inking the surfaces of the line units, taking an impres- 85 sion therefrom upon a light-transmitting, impression-receiving surface, sensitizing the surface of a printing plate, transferring the composed matter from the said impression-receiving surface to the surface of the said plate by the action of light, and preparing 90 the said plate for printing.

In testimony whereof, I have signed my name to this specification, in the presence of two subscribing witnesses.

GEORGE R. CORNWALL.

Witnesses:

JOHN D. MORGAN,
CLARA PHILLIPS.
